HUMIDIFIER

Gerald W. Skilbeck, Kenosha, Wis.

Application December 8, 1942, Serial No. 468,191

9 Claims. (Cl. 237—78)

This invention relates to improvements in humidifiers of the type used with steam heating systems or with any suitable source of steam.

In general, humidifiers of this type are supplied with steam from a source thereof and in one manner or another convert the steam to a vapor suitable to be discharged into the atmosphere of a room to humidify the same.

Various designs of humidifiers have been proposed for this purpose among which is the humidifier forming the subject matter of Patent No. 2,111,437 issued to Gerald W. Skilbeck, March 15, 1938. All of these past humidifiers, however, have been objectionable from the standpoint that they are incapable of satisfactorily handling the relatively large accumulation of condensate which forms therein during their operation.

In the aforementioned Skilbeck patent an overflow for condensate was embodied in the humidifier which overflow supplied an exposed asbestos evaporating pad with moisture capable of exerting a humidifying influence on the surrounding atmosphere.

Most other types of humidifiers attempt to evaporate the condensate and thus inject moisture into the atmosphere, but this procedure is obviously objectionable in that complicated constructions embodying float operated valves are required, while the capacity of such humidifiers is obviously limited to an almost negligible amount unless an extremely large reservoir for the condensate is provided. Even then, the slow process of evaporation is utterly incapable of maintaining 40 to 50% relative humidity in the atmosphere of a building or room during cold weather conditions.

With the above and other objections to past humidifiers in mind this invention has as its object the provision of a small compact humidifier of extremely simple construction and which is designed to solve the problem of the accumulated condensate hereinbefore mentioned.

A further object of this invention is to provide a humidifier of the character described with an outer steam receptacle and an inner humidifying receptacle in telescoping relationship therewith so that said inner receptacle is superheated by the steam in the outer receptacle to reduce condensation in the humidifying receptacle to an insignificant minimum.

Another object of this invention is to provide a humidifier of the character described for connection to a steam radiator or a similar source of steam under pressure with means including

a water seal for controlling the discharge of condensate back to the source of steam.

Still another object of this invention is to provide a humidifier of the character described which though small and compact is capable of continuously discharging large quantities of water vapor into the atmosphere, and which is capable of maintaining any predetermined high level of humidity.

10 With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawing illustrates two 20 complete examples of the physical embodiment of the invention constructed in accordance with the best modes so far devised for the practical application of the principles thereof, and in which:

25 Figure 1 is an elevational view of a conventional steam heating radiator shown connected with a riser for supplying the radiator with steam and illustrating the application of the humidifier of this invention thereto;

30 Figure 2 is an enlarged vertical sectional view through the humidifier per se;

Figure 3 is an enlarged sectional view taken through Figure 2 on the plane of the line 3—3; and

35 Figure 4 is a modification illustrating the humidifier of this invention built into one of the sections of a steam radiator.

Referring now more particularly to the accompanying drawing in which like numerals indicate 40 like parts, the numeral 5 represents a conventional steam heating radiator which as is customary comprises a plurality of spaced vertical radiator sections or flanges communicated at their upper and lower ends.

45 The top of one end section 6 of the radiator is connected through a valved supply pipe 7 with a source of steam under pressure such as the riser 8 so that steam is free to flow into the radiator sections whenever the valve 9 in the pipe line 7 is open.

An outlet pipe (not shown) usually connected with the opposite end section of the radiator provides for the return of the condensate in the customary manner.

55 The humidifier 10 of this invention is adapted

to be mounted either on one of the end sections 6 of the radiator or directly on the riser 8. If desired, a humidifier can be mounted on both the radiator and the riser so that in the event of closure of the valve 24 the humidifier on the riser still remains operative.

The humidifier proper comprises an upright receptacle 12 preferably formed from a length of tubing 13 the ends of which are closed by caps 14. Mounted inside the receptacle adjacent to its upper end is a humidifying chamber or receptacle 15. The humidifying receptacle 15 is preferably cup-shaped and has its side wall in spaced telescoping relationship to the side wall of the receptacle 12 so as to form a steam jacket 16 therebetween. An expanded rim 17 at the upper open end of the inner humidifying receptacle substantially closing the upper end of the shell 13 is brazed or soldered to the shell to mount the humidifying receptacle within the outer receptacle 12.

The outer receptacle 12 is provided with a nipple 18 having a bore providing an inlet port 19 through the side of the receptacle so that when the nipple is threaded into a suitable opening 20 in either the end section 6 of the radiator or the riser 8 steam under pressure flows into the interior of the outer receptacle in a volume depending upon the size of the inlet port 19.

A tube 21 connects the bottom of the outer receptacle 12 with the radiator or riser at a point spaced a substantial distance below the nipple 18 and this tube is bent adjacent to its connection with the radiator or riser so that the bend is at 22 to form a water seal indicated generally by the numeral 23. The tube 21 and its water seal provides for the controlled return of the condensate which forms in the receptacle 12 and collects in the tube to the interior of the radiator or the pressure line 8 in a manner to be later described.

Steam is conducted from the interior of the receptacle 12 to the interior of the humidifying receptacle 15 by means of a valve 24 having a restricted inlet port 25 and a pair of vertically spaced discharge ports 26. The valve is mounted in an upright position on the bottom wall 27 of the humidifying receptacle with its inlet 25 communicating with the interior of the outer receptacle and has an adjusting screw 28 threaded therein to provide means for limiting the free motion of a ball check 29 which serves to close the inlet port 25 against the admission of air into the radiator through the humidifier and which governs the amount of steam flowing into the interior of the humidifying receptacle depending upon the adjustment of the screw 28. The outer end of the screw 28 projects through a hole in the upper cap 14 and is slotted to facilitate adjustment of the valve.

The volume of steam flowing into the inner receptacle through the valve 24 thus depends upon the size of the port 25 and the amount of free motion of the valve under the influence of steam pressure. The adjusting screw 28 is capable of being turned down to a position at which it holds the ball 29 in a position closing the port 25 at which time the humidifier is rendered inoperative, or it may be adjusted to a position such as shown in Figure 3 permitting a maximum volume of steam to be discharged into the interior of the inner humidifying receptacle through the port 26.

Because of the fact that the inlet port 25 of the valve is smaller than the inlet 19 for the outer

receptacle 12, pressure within the humidifying receptacle 15 is always less than that of the outer receptacle thus insuring quiet operation of the humidifier. To further guard against noise, the bottom of the inner receptacle is packed with a quantity of metal wool 30, preferably copper, and a superimposed washer 31 of asbestos or other similar material, held in place by a washer 32. A clamping nut 33 threaded onto the upper exterior of the valve and loosely encircling the screw 28 firmly holds the filling in the bottom of the inner receptacle about the discharge ports 26 of the valve.

Steam discharging into the inner receptacle through the port 25 and the outlets 26 of the valve reaches the atmosphere through a downwardly extending tube 34 fixed to the upper cap 14 and which directly communicates the interior of the receptacle with the atmosphere.

One of the main features of the humidifier of this invention resides in the fact that nearly all of the condensation in the unit takes place in the outer receptacle 12 from whence it flows into the discharge tube 21 to be returned to the steam pressure line or radiator as shown.

When the device is initially placed in operation, it will be understood that much of the steam entering the outer receptacle 12 will be condensed and the water of condensation will flow down through the tube 21 and rather quickly establish the water seal 23. The rate of condensation will rise in the tube 21 until the weight of the water in the tube compensates for the reduction in pressure effected within the outer receptacle 12 by reason of the escape of steam therefrom into the inner receptacle 15. At this point the reduced pressure within the receptacle 12 plus the weight of water within the tube 21 equals the pressure applied to the discharge of the water seal 23, and during continued operation of the humidifier, water will be returned to the pressure system in accordance with the amount of condensation taking place within the outer receptacle 12.

Inasmuch as the humidifier of this invention may be used on so called high pressure steam heating systems the tube 21 is preferably elongated to an extent permitting the maintenance of a much higher level of water therein than that shown.

Consequently it will be seen that throughout the operation of the humidifier the return of the condensate back into the pressure line 8 or radiator is controlled by means of the pressure balance effected between the steam system and the combined effect of reduced pressure within the outer receptacle 12 and the weight of water in the tube 21.

While the humidifying unit described is an independent unit capable of being attached to any steam radiator or riser it is also possible to install the same in radiators at the time of their manufacture as illustrated in Figure 4.

As here shown one of the radiator sections 6' for the radiator is cast with a laterally extending chamber 40 having a threaded opening 41 in its top wall closed by a correspondingly threaded supporting collar 42 to which the humidifying receptacle 15' is secured as by threads 43. The humidifying receptacle 15' thus is detachably held by the collar 42 within the chamber 40, to be exposed to and supplied with steam in the radiator, it being understood that the humidifying receptacle 15' is similar in all re-

spects to that described with the exception of the screw threads at its upper open end.

Also in this instance the mounting collar 42 carries the downwardly depending tube 34' which directly communicates the interior of the humidifying receptacle with the atmosphere, and has a hole therein through which the valve adjusting screw 28' projects to the exterior of the radiator.

In both embodiments of the invention, it will be appreciated that some slight degree of condensation will take place within the humidifying receptacle, but such an occurrence is desirable for the reduction of steam odors. The condensate collecting in the bottom of the humidifying receptacle is boiled off by the steam in the outer receptacle 12 or the chamber 40 and in the steam jacket 16, and the vapor in rising through the asbestos washer is filtered to further reduce odors.

From the foregoing description taken in connection with the accompanying drawing, it will be readily apparent to those skilled in the art, that this invention provides an exceedingly simple but efficient humidifier which though small in size has an exceptionally large capacity for humidifying purposes, and which provides for the return of condensate back to the steam lines in a novel manner.

What I claim as my invention is:

1. In a humidifier of the character described: a high pressure chamber having an inlet port therein through which steam under pressure from a source thereof is admitted for subsequent discharge to the atmosphere, said high pressure chamber having a discharge port therein adjacent to the bottom of the chamber; and means for returning condensate formed in said high pressure chamber to said source of steam and against the pressure of steam at said source comprising a duct connected between the discharge port and the steam source, and a water seal in the duct, said duct having a vertical length such as to accommodate a column of water therein which in conjunction with the pressure obtaining in the chamber overcomes maximum steam pressure at the discharge end of the duct whereby condensation formed in the chamber accumulates in the duct and has substantially no temperature modifying influence on the steam entering the chamber and whereby said accumulated condensate is returned to the source of steam in a controlled manner substantially continuously during operation of the humidifier whenever the weight of condensate in the duct offsets the difference in pressures existing in the chamber and the source of steam.

2. In a humidifier of the character described: a high pressure chamber having means for introducing steam under pressure thereto from a source thereof for subsequent discharge to the atmosphere, said high pressure chamber having a discharge port therein adjacent to its bottom; means for returning condensate formed in said high pressure chamber to said source of steam against the pressure thereof comprising a duct connected between the discharge port and the steam source; and means in the duct for permitting condensate formed in the chamber to collect in the duct despite the application of maximum steam pressure from the source to the discharge end of the duct, said duct having a vertical length such as to accommodate a column of collected condensate therein which in conjunction with the pressure obtaining in the chamber at least bal-

ances steam pressure at the discharge end of the duct whereby overbalancing amounts of condensate collected in the duct are returned to the source of steam under pressure, and said duct connecting with the steam source in non-communicating relationship with said means for introducing steam to the high pressure chamber so as to preclude condensate returned to the steam source from being blown back into the high pressure chamber.

3. In a humidifier of the character described including a chamber having means for introducing steam thereto from a source of pressure and for discharging steam to the atmosphere, and having a discharge port therein adjacent to its bottom, means for returning condensate formed in the chamber to said source of steam pressure comprising: a duct connected with said port in the bottom of the chamber and having its discharge end connected to the source of steam under pressure entirely independently of the means for introducing steam to the chamber and at a point spaced a distance therefrom; and means in the duct by which condensate formed in the chamber is allowed to collect in the duct despite the application of maximum steam pressure from the source to the discharge end of the duct, said duct being of sufficient vertical length as to accommodate a weight of condensate therein which at least equals the pressure differential existing between the chamber and the steam source whereby such condensate which exceeds said pressure differential is returned to the steam source against the pressure thereof and whereby all of the condensate formed in the chamber is capable of being accommodated in the duct during operation of the humidifier.

4. In a humidifier of the character described: a high pressure chamber into which steam under pressure from a source thereof is admitted for controlled discharge to the atmosphere, said chamber having a discharge port in its lower portion through which condensate formed in the chamber is discharged; a reservoir wholly exteriorly of the chamber for collecting such condensate; and means entirely independent of the steam inlet for the high pressure chamber for connecting said reservoir with the source of steam under pressure and for enabling condensate to collect in the reservoir against the opposition of maximum steam pressure from the source until the weight of collected condensate exceeds the pressure differential between the steam source and said high pressure chamber and to thereafter return such condensate in excess of the pressure differential to the source of steam under pressure, said reservoir being large enough to hold such collected condensate so that it has substantially no temperature modifying influence on the steam admitted to the high pressure chamber.

5. In a humidifier of the character described: a high pressure chamber into which steam under pressure from a source thereof is admitted for controlled discharge to the atmosphere; non-communicating steam inlet and condensate discharge means for supplying steam under pressure to said chamber from a source thereof and for returning the condensate to said source, respectively, said discharge means being connected to the chamber at a lowermost portion thereof; and means forming a part of the discharge means for effecting a seal therein for preventing steam from the source from backing up through the discharge means toward the high pressure chamber and to thereby permit condensate to collect in

the discharge means, said last named means permitting the return of condensate to the source of steam pressure whenever the weight of collected condensate in said discharge means in conjunction with the pressure within the high pressure chamber exceeds the pressure at the steam source.

6. A humidifying device of the character described comprising: an upright outer receptacle closed except for discharge openings in its top and bottom portions and a side inlet substantially medially thereof; means for mounting the receptacle on a steam pressure duct with its side inlet in communication with the interior of the duct so that steam under pressure flows into the receptacle; an inner humidifying receptacle substantially closing the upper portion of said outer receptacle and having its interior communicating with the atmosphere through the upper discharge opening of the outer receptacle; a valve opening in response to steam pressure within the outer receptacle for admitting steam into the humidifying receptacle and consequently to the atmosphere; and a tube projecting downwardly from said lower discharge opening in the outer receptacle for connection to the steam duct at a point spaced a distance from said mounting means for the receptacle and having a vertical length such as to accommodate a weight of condensate therein at least equal to the pressure differential between steam pressure in the duct and that of the outer receptacle whereby condensate formed in the outer receptacle collects in the tube exteriorly of the outer receptacle, and said tube being shaped in such a manner that condensate collected therein forms a water seal for preventing steam in the duct from backing up through the tube while permitting collected condensate in excess of said pressure differential to be discharged to the duct against the pressure thereof.

7. A humidifying device of the character described comprising: an outer receptacle open at its top and having a discharge opening in its bottom portion and a side inlet for the admission of steam thereto; means for mounting the receptacle on a steam pressure duct with its side inlet in communication with the interior of the duct so that steam under pressure flows into the outer receptacle; an inner humidifying receptacle substantially closing the upper portion of the outer receptacle and having its interior communicating with the atmosphere through the open end of the outer receptacle, said inner humidifying receptacle having a port for admitting steam thereto from the outer receptacle, the passage of steam from the outer receptacle to the inner humidifying receptacle causing steam pressure in the outer receptacle to be less than that obtaining within the steam duct; a tube projecting downwardly from said lower discharge opening

in the outer receptacle for connection to the steam duct at a point spaced a distance from said mounting means for the humidifier and having sufficient vertical length to accommodate a weight of condensate therein at least equal to the pressure differential between the duct and outer receptacle whereby condensate formed in the outer receptacle collects in the tube, said tube being shaped in such a manner that condensate collected therein forms a water seal for preventing steam in the duct from backing up through the tube while permitting collected condensate in excess of said pressure differential to be discharged to the duct against the pressure thereof; a pressure responsive valve for controlling the admission of steam to the humidifying receptacle adapted to close in the absence of steam pressure; and means accessible at the exterior of the device for determining the extent to which the valve opens and for enabling closure of the valve at will.

8. A humidifier of the character described having a chamber to which steam is admitted for controlled discharge to the atmosphere, characterized by: non-communicating steam inlet and condensate discharge means for supplying said chamber with steam from a source of steam under pressure and for returning condensate formed in said chamber to the same source of steam; and by the provision of means in said condensate discharge means whereby condensate collected therein prevents steam from the source from backing up into said chamber through the discharge means and the condensate collected therein.

9. A humidifier of the character described having a chamber to which steam from a source is admitted for subsequent discharge to the atmosphere and in which the discharge of steam from said chamber causes pressure therein to be less than at the source of steam characterized by: the provision of condensate discharge means connected with the chamber at a lowermost portion thereof and so formed that collected condensate in said discharge means prevents steam from the source from backing up through the collected condensate toward the chamber with a predetermined maximum pressure at the source and a predetermined maximum pressure differential between the chamber and the steam source; and further characterized by the provision of means for obtaining said predetermined pressure differential despite higher pressures than said predetermined maximum pressure at the source of steam whereby the level of condensate in said discharge means may be prevented from rising in correspondence to higher steam pressures at the source.

GERALD W. SKILBECK.
